UNITED STATES PATENT OFFICE.

ALFRED E. JOHNSON, OF DENVER, COLORADO, ASSIGNOR TO THE ILLER ROCK DRILL MANUFACTURING COMPANY, OF DENVER, COLORADO.

HAMMER-DRILL.

No. 870,178.

Specification of Letters Patent.

Patented Nov. 5, 1907.

Application filed February 23, 1906. Serial No. 302,373.

To all whom it may concern:

Be it known that I, ALFRED E. JOHNSON, a citizen of the United States, residing at the city and county of Denver, and State of Colorado, have invented certain new and useful Improvements in Hammer-Drills; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in hammer drills or tools in which the reciprocating part or hammer is not directly connected with the drill bit or tool, the said part being actuated by air or other suitable operating fluid.

My present invention relates only to certain novel features of construction which are considered improvements over the construction disclosed in Letters Patent No. 789,916, issued to me May 16th, 1905. The distinguishing feature of the construction set forth in the aforesaid patent, consists of a hollow conduit preferably constructed in the form of a crank, the said conduit being connected with the body of the drill or tool to be operated at one extremity and with an abutment at the opposite extremity in which the rear extremity of the conduit is journaled. The motive fluid for operating the tool is introduced to the hollow conduit at its abutment extremity. My present invention relates to the particular construction of the rear extremity of the hollow conduit and the sleeve of the abutment into which this rear extremity protrudes. In my present improvement this rear extremity with the hollow conduit consists of a spindle member detachably connected with the body of the conduit and having a passage communicating therewith. This passage also communicates with ports formed in the spindle which in turn communicate with a chamber of the abutment, when the latter is moved forwardly on the spindle for operating purposes. The rear extremity of the spindle member of the conduit has an enlarged head around which the motive fluid is allowed to circulate in the abutment chamber. The forward extremity of this head consists of a beveled face which when the abutment is at its rearward limit of movement, engages a shoulder of the abutment sleeve, leaving a space between the beveled face of the spindle head and the angle formed with the shoulder of the sleeve. The induction port of the sleeve communicates with the forward extremity of

the chamber of the sleeve, thus allowing the motive fluid to enter the space in the sleeve between the beveled head of the spindle and the shoulder of the sleeve, when the abutment is at its rearward limit of movement. By virtue of this construction, the operator in moving the abutment forward to begin the operation of the device, does not have to push against the entire pressure acting against the rear end of the abutment proper, since the action of the fluid on the shoulder of the abutment reduces the effective pressure area to a considerable extent. This is an improvement over the original construction set forth in the said patent.

Having briefly outlined my improved construction, I will proceed to describe the same in detail, reference being made to the accompanying drawing, in which is illustrated an embodiment thereof.

In the drawings, Figure 1 is a longitudinal section taken through a hammer drill equipped with my improvements. Fig. 2 is a fragmentary view of the same showing the parts on a larger scale, the relative position of the abutment and hollow crank being the same as in Fig. 1. Fig. 3 is a view similar to Fig. 2 but showing the abutment and hollow crank in different relative positions.

The same reference characters indicate the same parts in all the views.

Let the numeral 5 designate the body of the tool, 6 the drill bit or steel arranged to be acted on by the hammer 7 which as shown in this instance acts directly on a tappet 4 interposed between the hammer and drill bit. This hammer may consist of any desired form of reciprocating striker. In this instance its general shape is cylindrical and it is mounted to reciprocate in a chamber of corresponding shape formed in the body or casing 5 of the tool. In this instance the hammer is adapted to move through a valve sleeve A whose extremities are provided with pressure surfaces of different areas.

Suitably connected with the rear extremity of the cylinder 5 is the hollow crank 8. In this instance the forward extremity of this crank is connected with the cylinder by a clamping sleeve 9 formed integral with the hollow crank but split a short distance from its extremity as shown at 10 to give the necessary clamping capacity. Through this split portion of the sleeve is passed a bolt 12 whereby the crank is securely fastened to the body 5 of the tool. To facilitate the securing of the two parts together, the sleeve together with the rearward extremity of the body of the tool is threaded. After the threaded connection is made the parts are

further secured by clamping as just explained. It is evident; however, that any desired or suitable means of connecting the hollow crank with the body of the tool may be employed.

- 5 The rear extremity B of the hollow crank preferably has its center in line with the longitudinal center or axis of the body of the tool while its part C occupies a position at any desired distance from said center according to the desired leverage. The part B is fixedly connected with a hollow spindle 13. In this instance the forward extremity of the spindle or that farther to the right in the drawing is threaded into the extremity B of the crank. This extremity of the crank has a chamber 14 which the hollow spindle enters and with which the hollow of the spindle communicates by means of ports 15. The rear extremity of the spindle part 13 of the crank, enters a sleeve 16 which is provided with a suitable packing 17 to form a fluid tight joint between the sleeve and the spindle in order to prevent leakage of the operating fluid. The rear extremity of the part 13 has an enlarged part or head 18. This head is adapted to slide freely in a chamber 19 formed in the rear portion of the sleeve 16. The rear extremity of the sleeve is closed by the abutment proper 20 which has a threaded lug 21 which enters the interiorly threaded rear portion of the sleeve. The ports 15 of the part 13 communicate at their inner extremities with a longitudinal passage 22 formed in the spindle, the latter being also provided near its rear extremity with ports 23 which communicate with the sleeve chamber 19 when the parts are in the relative position shown in Fig. 3.
- The chamber 19 of the sleeve communicates at its forward extremity with a port 24. Outside of this port is formed an interiorly threaded projection 25 adapted to receive a conduit (not shown) for supplying the necessary operating fluid. The head of the hollow spindle part of the crank is provided with a rearwardly located inclined or beveled face 18^a which engages the corner of an abrupt shoulder 26 formed on the sleeve, thus leaving a space 27 between the said face and the shoulder angle of the sleeve which space receives the operating fluid when the abutment is at its rearward limit of movement (see Figs. 1 and 2). The head 18 does not fit tightly within the chamber 19 of the sleeve, but the parts are so formed as to allow the operating fluid to pass the said head and occupy a position between the abutment and the spindle head whereby it forms a cushion and relieves the operator from the annoyance due to the vibration of tools of this character.

Assuming that the crank and abutment are in the relative position shown in Fig. 1, if fluid be introduced at the port 24, it will pass to the chamber 19 and also to the space between the face 18^a of the spindle and the adjacent angle of the sleeve. When the parts are in this position no fluid passes through the hollow crank to the tool, since the ports 23 are located forward of the port 24, and the opening 22 of the spindle is not continued through the head thereof. Now if the operator desires to pass the fluid through the hollow crank to the tool, he presses upon the abutment 20 and slides the same forward on the spindle until one or both of the ports 23 enter the sleeve chamber 19 (see Fig. 3), in which event the fluid passes through the duct 22 of the spindle, through the ports 15 to the

chamber 14 of the hollow crank and thence through the angular passage 28 of the crank, to an annular chamber 29 formed in the clamping sleeve 9. From this chamber 29, the fluid passes through ports 30 formed in a detachable part 31 of the cylinder, into a circumferential groove 32 formed on the inside of the part 31 and surrounding the outer surface of the sleeve valve A. Now assuming that the hammer is at its forward limit of movement as shown in Fig. 1, and that the sleeve valve is at its rearward limit of movement, the operating fluid which has driven the hammer forward has exhausted through ports 33 formed in the valve, into a circumferential groove 34 formed in the member 31, the exhaust passing thence through rearwardly-extending openings 35 (indicated by dotted lines in Fig. 1) to the exhaust chamber 36 and thence to the atmosphere through a passage 37. A small part of the operating fluid, however, enters a transverse passage 38 formed in a member 39 and passes thence through a duct 40 formed in a forwardly-extending stem 41 of the member 39, passing thence outwardly through ducts 42 into an annular space 43 formed in the rear extremity of the hammer and communicating by means of ducts 44 with longitudinal grooves 45 formed in the outer wall of the hammer and communicating with the forward extremity of the sleeve valve. It is the action of this fluid which has imparted the rearward movement to the valve or caused it to occupy the position shown in Fig. 1. This fluid also flows through a central passage 47 of the hammer and escapes therefrom through passages 48 to a chamber 49 where the fluid acts to return the hammer to its rearward limit of movement. After the hammer during this rearward movement passes the exhaust ports 33 of the valve, the motive fluid cushions between the rear extremity of the hammer and the chamber in the rear of the exhaust ports and the resulting fluid pressure acting on the relatively small surface area of the rear extremity of the valve, imparts the forward movement to the valve and brings its ports 33 into communication with the interior circumferential groove 32 of the member 31, allowing the motive fluid to pass to the hammer chamber, the ports 33 of the valve which have heretofore been designated as exhaust ports, now becoming induction ports. The fluid cushion in the rear of the hammer as it is completing its rearward stroke, reacts on the hammer and imparts thereto a forward movement sufficient to bring its rear extremity forward of the valve ports 33 when the valve is at its forward limit of movement, thus allowing the motive fluid to enter behind the hammer and act thereon to impart its forward or working stroke.

In the construction shown, the motive fluid forward of the hammer during a part of the latter's forward strike, escapes into a circumferential groove 50 formed in the inner wall of the cylinder and passes thence through ducts 51, 52 and ports 53, to the drill steel or bit which it is assumed is provided with a passage for delivering the fluid to the inner extremity of the drill hole for the purpose of cleaning out the latter.

As nothing is claimed on the specific construction of hammer or striking mechanism in this application the said mechanism and its principle of operation will not be further set forth in detail.

As soon as the operator ceases to press on the abut-

ment, the action of the motive fluid in the chamber 19, throws the abutment to its rearward limit of movement and automatically cuts off the supply of fluid from the hollow crank and the tool to be operated.

5 Having thus described my invention, what I claim is:

1. In a construction of the class described, the combination with the body of the tool, of a hollow crank rigidly connected with the tool at one extremity, a hollow spindle detachably connected with the opposite extremity of the 10 crank and communicating with the passage way of the crank, an abutment having a chamber into which one extremity of the spindle protrudes, the hollow of the spindle being in communication with said chamber, the part of the spindle within the abutment chamber being enlarged to 15 form a head provided with a beveled front face located opposite a shoulder of the abutment when the latter is at its rearward limit of movement, the spindle and its head being free to slide in the sleeve of the abutment the latter being provided with a fluid induction port located at the 20 forward extremity of the abutment chamber and communicating with the space between the beveled face of the spindle and the shoulder of the abutment, the extremity of

the spindle and its head within the abutment chamber being of a size to allow the motive fluid to pass therearound for the purpose set forth.

25

2. In a hammer drill, the combination with the body of the instrument, of an abutment, a hollow member connecting the body of the tool with the abutment, the abutment extremity of the crank consisting of a hollow spindle detachably connected with the said hollow member and having an enlarged head located within a chamber formed in the abutment, the spindle and its head being free to slide in the said chamber the said head being provided with a beveled forward face and the abutment with a shoulder located opposite the said face when the abutment is at its rearward limit of movement, the abutment being provided with a motive fluid induction port communicating with the abutment chamber.

30

In testimony whereof I affix my signature in presence of two witnesses.

ALFRED E. JOHNSON.
